UNITED STATES PATENT OFFICE

164,394

TUG BOAT

Walter Wiggins, Jr., Beaver Heights, Md.

Application April 16, 1951, Serial No. 14,849

Term of patent 14 years

(Cl. D71—1)

To all whom it may concern:

Be it known that I, Walter Wiggins, Jr., a citizen of the United States, residing at Beaver Heights, in the County of Prince Georges and State of Maryland, have invented a new, original, and ornamental Design for a Tug Boat, of which the following is a specification, reference being had to the accompanying drawing, forming part thereof.

Figure 1 is a side elevational view of a tug boat, showing my new design;

Figure 2 is a top plan view thereof;

Figure 3 is a front end view, and

Figure 4 is a bottom plan view of the same.

I claim:

The ornamental design for a tug boat, as shown.

WALTER WIGGINS, JR.
